DESIGN FOR A TIRE CASING

Charles W. Yelm, Denver, Colo., assignor to The Gates Rubber Company, Denver, Colo., a corporation of Colorado

Application May 5, 1936, Serial No. 62,480

Term of patent 7 years

To all whom it may concern:

Be it known that I, Charles W. Yelm, a citizen of the United States, residing at Denver, in the county of Denver and State of Colorado, have invented a new, original, and ornamental Design for a Tire Casing, of which the following is a specification, reference being had to the accompanying drawing, forming part thereof.

Figure 1 is a section taken through the line
1—1 of Figure 2; and

Figure 2 is a fragmentary plan view of a portion of the tire casing, showing my new design.

I claim:

The ornamental design for a tire casing, as shown.

CHARLES W. YELM.
